(57) **CLAIM**

The ornamental design for a cutting device, as shown and described.

DESCRIPTION

FIG. 1 is a front left top perspective view of a cutting device showing our new design;

FIG. 2 is a front top perspective view thereof;

FIG. 3 is a right rear perspective view thereof;

FIG. 4 is a front elevation view thereof, the rear elevation view being identical;

FIG. 5 is a right side elevation view thereof, the left side elevation being identical;

FIG. 6 is a top view thereof;

FIG. 7 is a bottom view thereof;

FIG. 8 is an exploded view thereof with a first element, second element and third element shown separately for clarity;

FIG. 9 is an exploded view thereof with the first element and second element shown assembled and the third element shown separately;

FIG. 10 is an exploded view thereof with the first element shown separately and with the second element and the third element shown assembled;

FIG. 11 is a front left top perspective view of the first element of the cutting device shown separately;

FIG. 12 is a front top perspective view thereof;

FIG. 13 is a right rear perspective view thereof;

FIG. 14 is a front elevation view thereof, the rear elevation view being identical;

FIG. 15 is a right side elevation view thereof, the left side elevation being identical;

FIG. 16 is a top view thereof;

FIG. 17 is a bottom view thereof;

FIG. 18 is a front left top perspective view of the second element of the cutting device shown separately;

FIG. 19 is a right rear bottom perspective view thereof;

FIG. 20 is a front elevation view thereof;

FIG. 21 is a left side elevation view thereof;

FIG. 22 is a right side elevation view thereof;

FIG. 23 is a top view thereof;

FIG. 24 is a bottom view thereof;

FIG. 25 is a rear elevation view thereof;

FIG. 26 is a front left top perspective view of the third element of the cutting device shown separately;

FIG. 27 is a right rear top perspective view thereof;

FIG. 28 is a right rear bottom perspective view thereof;

(Continued)

FIG. 29 is a front elevation view thereof, the rear elevation view being identical;
 FIG. 30 is a right side elevation view thereof; the left side elevation view being identical;
 FIG. 31 is a top view thereof; and,
 FIG. 32 is a bottom view thereof.
